UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

RADIAL DRAFT-GEAR.

No. 900,022.

Specification of Letters Patent. Patented Sept. 29, 1908.

Original application filed May 11, 1906, Serial No. 316,296. Divided and this application filed August 18, 1906. Serial No. 331,203.

To all whom it may concern:

Be it known that I, HARRY T. KRAKAU, of Cleveland, Cuyahoga county, Ohio, have invented a new and useful Improvement in 5 Radial Draft-Gear, of which the following is a full, clear, and exact description, reference being had to the accompanying drawings, forming part of this specification, in which—

Figure 1 is a plan view partly in section of 10 a radial draft gear embodying my invention; Fig. 2 is a longitudinal section in part, showing a side elevation; Fig. 3 is a section on the line III—III of Fig. 2; Fig. 4 is a sectional detail view of the draft rigging; Fig. 5 is a 15 detail view of a portion of one of the guiding rods; Fig. 6 is a section on the line VI—VI of Fig. 5.

This invention has relation to a radial draft gear, this application being a division 20 of my application Serial No. 316,296, filed May 11th, 1906.

My invention provides a draft gear in which the coupler is capable of swinging laterally through a wide range and is connected 25 to the truck so as to be guided thereby positively into proper position. The device can be used with success on passenger cars, and can also be applied to draft-gears in a manner which will adapt them for use not only 30 with passenger cars, but also with much greater efficiency than heretofore on freight car equipments. The advantages of such laterally-swinging draft gears are, that they relieve the cars from the great strain to 35 which they are subjected when provided with laterally-fixed draft gears, and also remove the strain from the wheels, axles, and truck, and thus increase the durability of the cars and effect a very considerable economy in 40 the power required to move the trains.

The drawings show the preferred embodiment of my invention but it will be understood by those skilled in the art that the parts and their arrangement may be modified in 45 many ways and that some of the parts of the apparatus may be applied to use without the others.

In the drawings, 2 represents the car coupler, which has a long rear extension prefer- 50 ably made in the form of a shank 3 which terminates at the end in a socket 4 for a vertical pivot-pin 5. For convenience, I prefer to make the coupler-shank in two parts 3' and 3", the rear portion 3" being provided

with a socket or pin hole 4 and its front end 55 fitting between forks at the rear end of the forward portion 3" to which it is bolted. The socket 4 fits within yoke 6 to which it is attached by the pivot-pin 5, and the yoke is mounted between draft-irons 7, 7, 60 followers 8 being set cross-wise within the yoke and adapted to bear against stops 9 on the irons. A spring or springs 10 is inter- 65 posed between the followers and with the fol- lowers constitute the draft-rigging.

The coupler shank or extension is sup- 70 ported by carry irons b, b', and at its rear portion, the member 3' of the coupler shank is curved upwardly so as to bring the pin 5 and the yoke of the draft-rigging at substan- 75 tially the level of the car sills. Above the carry-iron b' the shoe c' is applied to the shank 3' at its lower part so as to give it full bearing on the carry iron and a good wearing surface.

When the car is in service, the coupler and its shank will turn radially on the axis of the pin 5, being guided by means described below, so that it will at all times be in approxi- 80 mately the central portion of the railway track. The draft-rigging, however, does not move laterally, but remains in the longitudi- 85 nal axis of the car, and as the coupler is subjected to the pressure of buffing and draft, the forward follower of the draft-rigging will 90 be forced back against the spring or the rear follower drawn forward against the spring, as the case may be, the forward stops 9 res- 95 sisting the force of draft and the rear stops 9 resisting the force of buffing.

To guide the coupler-shank and to hold it substantially at the center of the track, I provide it with guiding-rods shown in Fig. 1 which are made with telescopically-arranged sections having interposed springs 11 and at 95 their rear ends these rods are connected by ball-and-socket joints 12 to brackets 13 at the ends of the truck, and at their forward ends the rods are connected by ball-and-socket joints 14 with an-elbow-lever or like 100 connection 15 mounted at the middle on the vertical pin 16 forming part of a sleeve 16' mounted on the coupler-shank as shown in Figs. 2 and 3. This sleeve is preferably made in two sections divided horizontally 105 and adapted to fit slidingly on the top and bottom of the coupler-shank and it prefer- ably has inwardly-extending projections 16"

which are clamped by bolts 16^b between the sections of the sleeve and at their inner ends are made to fit against the web of the coupler-shank so as to afford a broad bearing surface for the sleeve 16. The telescopic rods serve as guiding connections between the coupler shank and the truck, and the sliding sleeve 16' permits the coupling shank to move longitudinally in buffing or in draft without moving the guiding connections to compress the springs therein, but the guiding connections will act on the coupler-shank to guide it to the center of the track no matter in what longitudinal position they may be. The advantages of the sliding connection in this respect, will be appreciated by those skilled in the art.

Within the scope of my invention as defined in the claims, those skilled in the art can modify the device in many ways since

What I claim is:—

1. A truck-connection for radial draft-gears comprising a rod having at its end a member of a ball-and-socket joint.
2. A truck-connection for radial draft-gears comprising telescopically intersifted rods having at the outer end of each a member of a ball-and-socket joint.
3. A center member of a truck-connection for radial draft-gears, said center member adapted to be secured to the draft-member and having on one side a member of a ball-and-socket joint.

In testimony whereof, I have hereunto set my hand.

HARRY T. KRAKAU.
